UNITED STATES PATENT OFFICE.

EUGENE A. JONES, OF LOS ANGELES, CALIFORNIA.

DESIGN FOR A TIRE.

50,873.

Specification for Design.

Patented June 5, 1917.

Application filed April 28, 1917. Serial No. 165,280. Term of patent 14 years.

To all whom it may concern:

Be it known that I, EUGENE A. JONES, a citizen of the United States, residing at Los Angeles, in the county of Los Angeles and State of California, have invented a new, original, and ornamental Design for Tires, of which the following is a specification, reference being had to the accompanying drawing, forming part thereof.

In the drawing,

Figure 1 is a side elevation, and Fig. 2 is a plan view, of a tire embodying my design.

I claim:

The ornamental design for a tire, as shown.

EUGENE A. JONES.

Witnesses:

LOUIS W. GRATZ,
ISABEL HALL.
